Primary Examiner — Paula Greene(74) *Attorney, Agent, or Firm* — Sheridan Ross P.C.(57) **CLAIM**

The ornamental design for a tool handle, as shown and described.

DESCRIPTION

FIG. 1 is a perspective view of the tool handle shown associated with a drill;

FIG. 2 is a perspective view of the tool handle;

FIG. 3 is a right elevation view thereof;

FIG. 4 is a left elevation view thereof;

FIG. 5 is a front elevation view thereof;

FIG. 6 is a rear elevation view thereof;

FIG. 7 is a bottom plan view thereof; and,

FIG. 8 is a top plan view thereof.

The broken lines make up no portion of the claimed design.

1 Claim, 8 Drawing Sheets(56)
